US00D859447S

(12) **United States Design Patent** (10) Patent No.: **US D859,447 S**
(45) Date of Patent: **** Sep. 10, 2019**

(54) **DISPLAY SCREEN OR PORTION THEREOF
WITH ANIMATED GRAPHICAL USER
INTERFACE**

- (71) Applicant: **Apple Inc.**, Cupertino, CA (US)
- (72) Inventors: **Freddy Anzures**, San Francisco, CA (US); **Greg Apodaca**, Mountain View, CA (US); **Sebastian Johannes Bauer**, San Francisco, CA (US); **Jonathan Dascola**, San Francisco, CA (US); **Alan C. Dye**, San Francisco, CA (US); **Christopher Foss**, San Francisco, CA (US); **Jonathan P. Ive**, San Francisco, CA (US); **Kenneth Kocienda**, San Jose, CA (US); **Lauren Kim Trottier**, San Jose, CA (US); **Wan Si Wan**, Sunnyvale, CA (US); **Giancarlo Yerkes**, Menlo Park, CA (US)
- (73) Assignee: **Apple Inc.**, Cupertino, CA (US)
- (**) Term: **15 Years**
- (21) Appl. No.: **29/635,973**
- (22) Filed: **Feb. 5, 2018**

CLAIM

The ornamental design for a display screen or portion thereof with animated graphical user interface, as shown and described.

DESCRIPTION

FIG. 1 is a front view of a display screen or portion thereof with animated graphical user interface showing a first image of the claimed design;

FIG. 2 is a second image thereof;

FIG. 3 is a third image thereof;

FIG. 4 is a fourth image thereof;

FIG. 5 is a fifth image thereof;

FIG. 6 is a sixth image thereof;

FIG. 7 is a front view of a display screen or portion thereof with animated graphical user interface showing a first image of another embodiment of the claimed design;

FIG. 8 is a second image thereof;

FIG. 9 is a third image thereof;

FIG. 10 is a fourth image thereof;

FIG. 11 is a fifth image thereof; and,

FIG. 12 is a sixth image thereof.

The outermost broken lines in the figures show a display screen or portion thereof, and form no part of the claimed design. The other broken lines in the figures show portions of the animated graphical user interface that form no part of the claimed design.

The appearance of the animated image sequentially transitions between the images shown in FIGS. 1-6 and FIGS. 7-12, respectively. The process or period in which one image transitions to another forms no part of the claimed design. The figures are illustrated with white, light gray and dark gray shading to show contrasting appearance; no particular color is claimed.
